CLAIM

I claim, the ornamental design for a home theater chair, as shown and described.

DESCRIPTION

FIG. 1 is a perspective view of a home theater chair, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a perspective view of the home theater chair of FIG. 1 with an armrest in a retracted position;

FIG. 8 is a perspective view of the home theater chair of FIG. 1 with a footrest in an extended position;

FIG. 9 is a perspective view of the home theater chair of FIG. 1, with the storage drawers in an open position;

FIG. 10 is a front perspective view thereof;

FIG. 11 is a left side view thereof;

FIG. 12 is a right side view thereof; and,

FIG. 13 is a top view thereof.

Broken lines are used in the drawings to show portions of the home theater chair that form no part of the claimed design.
